EUGENE M. BOURNONVILLE, OF JERSEY CITY, NEW JERSEY.

ROTARY VALVE FOR INTERNAL-COMBUSTION ENGINES.

1,250,548.

Specification of Letters Patent. Patented Dec. 18, 1917.

Application filed February 14, 1917. Serial No. 148,503.

To all whom it may concern:

Be it known that I, EUGENE M. BOURNONVILLE, a citizen of the United States, and a resident of Jersey City, in the county of Hudson and State of New Jersey, have invented certain new and useful Improvements in Rotary Valves for Internal-Combustion Engines, of which the following is a specification.

10 The invention relates to internal combustion engine valves of the type comprising a rotor turning in the bore of a casing, and embraces certain novel features in respect to the rotor and its casing having for their general object to improve the lubrication and to reduce the possibility of sticking and scoring of the valve.

In the accompanying drawings illustrating the improvements:

10 Figure 1 is a vertical longitudinal section through the upper part of a multicylinder engine embodying the improvements;

15 Fig. 2 is a projection of the surface of the rotary valve member;

Fig. 3 is a longitudinal section through a portion of the rotary valve member;

Fig. 4 is a transverse section on the line 4—4 of Fig. 3;

Fig. 5 is an enlarged transverse section on the line 5—5 of Fig. 1;

Fig. 6 is a transverse section on the line 6—6 of Fig. 3;

Fig. 7 is a transverse section through the rotary valve member showing an alternative construction; and

Fig. 8 is a fragmentary longitudinal section on the line 8—8 of Fig. 7.

In the valve selected for illustration, a cylindrical rotor 2 finds its bearing in the bore of a water-cooled casing 3 extending over the tops of the cylinders 4 of a multi-

cylinder internal combustion engine, with which the bore communicates by ports 5. Intake and exhaust openings 6 and 7 are formed at opposite sides, with the cylinder ports between them, the intake opening communicating with a manifold 8 formed in the body of the casing and the exhaust opening with a suitable external manifold not shown.

0 The intake opening preferably extends substantially continuously for the length of the bore; or intake ports for the respective cylinders may be connected by a passage in the face of the bore to secure a like effect. The

5 form of rotor illustrated has lateral pockets 9 constituting transfer ports, which connect

the intake and exhaust ports alternately with the cylinder ports; and there may be two or three of these pockets for each cylinder, so that the valve turns at one-quarter or one-sixth the speed of the crank-shaft. Part or all of the fresh fuel mixture from the carburetor traverses a longitudinal passage 10 in the interior of the rotary valve body before entering the intake manifold, from which the charges are admitted to the cylinders by the pockets 9 at the proper times. The valve is preferably lubricated and sealed by lubricating oil introduced into the fuel, or into the fuel and air mixture, and carried thereby to the surface of the rotor upon which it is deposited. A valve thus constituted is of the kind disclosed in my Patents, No. 1,118,730 of November 24, 1914, and No. 1,119,494 of December 1, 1914, and my application, Serial No. 65,655, filed December 8, 1915, to which the present improvements are particularly applicable though not necessarily confined. In the specific construction selected for illustration herein the fresh gases which flow through the valve passage 10 enter it at one end, marked 11, and pass out at the opposite end through the connection shown at 12 into the adjacent end of the manifold 8, but the gases 85 may also be admitted to the interior of the valve at the middle and flow out at both ends as disclosed in one form of my said application.

As in my prior cases the rotary valve member is made in two or more sections flexibly jointed between cylinders, as represented at 13. A joint sleeve 14 loosely held in enlargements of the passage 10 at the adjoining ends of the sections bridges the joint to prevent undue freedom of passage therethrough.

Heretofore the great difficulty with rotary valve internal combustion engines, namely the tendency of the rotary member exposed to the heat of the exhaust to bind in its casing, has caused those engaged upon the problem to seek to make the respective bearing surfaces as smooth and as absolutely cylindrical as possible. Contrary to expectation, I have made the discovery that beneficial results in the avoidance of sticking are obtained by providing a rotor with a multiplicity of low regions, superficial as to depth and of relatively large area, distributed in any desired or irregular manner over the exterior of the member, so that

there is an overlapping of the areas throughout the length of the valve. The interior surface of the casing is preferably made smooth. The effect of these low areas is to 5 carry around film patches of lubricant, which continually restore the oil film between the rotor and casing which keeps the metal surfaces from touching. Such superficial low regions it will be understood are 10 to be distinguished from grooves cut into the valve, from which they differ both in structure and effect. While their precise depth may naturally vary, a range of a quarter of a thousandth to three or four 15 one-thousandths of an inch is believed to be fairly illustrative. The low areas in question are indicated in Fig. 2, where they are designated by the reference character 15.

As a further means of promoting lubrication and sealing, the rear side of the longitudinal opening 6 in the inner wall of the casing which communicates with the intake manifold, is beveled at its inner edge, as indicated at 16 in Fig. 5, so as to cause 20 the oil deposited from the fuel mixture upon the face of the valve member to be urged as the result of the rotation of the latter into a wedge-like entrance, whence it is carried onward between the surfaces. The 25 behavior of such an internally-beveled edge is directly opposed to that of a sharp or square edge, which acts as a wiper. By the rear side of the intake port or opening I mean, of course, the side which is the later 30 35 to be encountered by a given point on the valve member in the revolution of the latter.

I have also observed that at the end of a run a certain amount of lubricating oil is left within the central valve passage 10, 40 which when the engine is started again is drawn into the cylinders in sufficient quantity to cause an objectionable amount of smoke in the exhaust. To overcome this difficulty and at the same time increase the 45 efficiency of the lubrication I now propose to provide the said interior passage between the pocket bearing portions of the valve with one or more encircling grooves 17, 17^a constituting recesses wherein such 50 de- posits are trapped by the action of centrifugal force as they move along the surface of the bore under the suction of the engine. Small channels 18 leading from the bottoms of the grooves 17 outward through 55 the wall of the valve to the member enable such trapped oil, still under the influence of centrifugal force, to reach the bearing surfaces of the rotor and casing, where it contributes to the maintenance of the de- 60 sired oil film. Short longitudinal oil grooves 19 may be formed in the outside of the rotary member into which the channels 18 open at their outer ends, the said grooves 65 preferably extending to within a short dis- tance of the ends of the valve pockets.

Where joints occur between the ported portions of the valve member, the encircling grooves in the central passage may be formed in the sleeve or sleeves 14, as is illustrated in the case of the groove 17^a. 70 It is then sufficient to carry channels 18^a only through the sleeve, since the break at the joint between the valve sections affords adequate passageway for the oil; and external grooves 19^a leading from the ends of 75 the valve sections perform the same function as the grooves 19.

The other great cause of sticking and cutting in these valves, in addition to failure of the oil film, is unequal expansion of the 80 rotor and casing as they become heated during the running of the engine. For this reason it is necessary to provide a certain amount of initial clearance between the rotary member and the bore in which it 85 turns, which diminishes as the engine heats up. This clearance requires to be carefully calculated, since if too little is provided the valve member will expand until it is gripped in the casing, while anything above what is 90 necessary to prevent the valve becoming tight in its bore when fully heated tends to diminish the power of the motor; on the other hand, because of the possibility of the engine becoming overheated at times from 95 various causes, it is necessary to allow a certain additional clearance above the theoretical requisite amount. In the case of low speed engines I have found that by proper construction of the valve, by efficient cooling 100 and lubrication, and by making the rotary member the proper amount smaller than the casing bore, for clearance as just described, it is possible to produce a rotary valve 105 which does not stick or score. With high speed engines, however, the same and even greater degree of care in these respects is not sufficient to insure against cutting, the recurrence of which in these motors has proved a problem particularly difficult of 110 solution. After study and experiment I have ascertained that the condition is caused by a differential expansion in the rotary valve member itself, the effect being a raising of the lips of the ports, which receive the hot 115 exhaust gases, above the general surface, sufficiently to produce a scraping or at least an excessive bearing at these regions, with resulting local destruction of the oil film at the places where it is most difficult to maintain, and eventual burning and cutting at the port zones. This detrimental action I now avoid by cutting down the surface of the rotary member at the edges of the ports 120 thereof to an extent which is sufficient to 125 compensate for the excessive expansion at these regions. Such cutting away is more important adjacent the front and rear longitudinal lips, and may be made more pronounced at one or other of these edges, 130

according to the particular conditions of operation. The lowering may be effected all the way around the port at the ends or transverse edges as well as at the front and rear sides. Cutting away of the surface of the valve member at the narrow or transverse edges of the ports, however, is of minor importance, and in fact it is sufficient to lower the surface only adjacent one of the longitudinal edges, that is to say the lip, which, depending upon the direction of rotation of the valve, is in the rear or following position. This lip at the time of exhaust is particularly exposed to the outflowing heated gases and subject to expansion, and if left full and sharp rises above the general surface so as to constitute a scraping edge which removes the lubricant from the face of the bore of the casing. By slightly cutting down or beveling the rear lip, the oil, instead of being scraped off, may be wedged in between the surfaces as the rotor revolves. A lowering extending all the way around the port is indicated at 20 in Fig. 2. The actual amount of cutting-away must depend upon the particular construction of the engine and valve, the diameter of the rotor, the amount of piston displacement, and in general upon the conditions determining the quantity of heat distributed through the valve in a given time. As a matter of measurement, the thickness of metal removed may range from, say, a half-thousandth of an inch for a two and one-half inch diameter valve to one-sixty-fourth of an inch for very large engines having valves up to twelve inches in diameter. In any particular case the extent of cutting-away must be determined by suitable calculation and trials. It will be understood that the illustration of the regions 20 in the sectional views is exaggerated.

The width of the lowered border at the edges of the valve ports will necessarily vary in different cases. For example, for a valve in the neighborhood of two and a half inches in diameter the region may be from one-quarter to one-half inch wide at the long sides and one-eighth to one-quarter inch wide at the ends, the borders being lowest at their inner edges, immediately adjacent the valve pockets, and merging into the general surface toward their outer portions. If desired the remainder of those parts of the surface of the valve member which are included in the port zones, that is to say, the regions extending circumferentially from the lowered borders 15, may also be cut down, but to a less extent, preferably about a quarter of the depression of said borders. It is to be understood, however, that the intent is not to eliminate bearing at the port zones, but rather to remove the material which would be in excess at these regions when the valve becomes heated,

and thus avoid the development of pressure at the said regions to the exclusion of the intermediate zones, so that the valve may have bearing in its casing for substantially its full length.

Another feature of the invention is the making of the insides of the ports or pockets of the valve member of separate pieces from the body, so as to diminish the amount of heat transmitted from the exhaust gases to the valve member. This may be effected by providing the pockets with sheet metal linings 21, suitably secured in place, as indicated in Fig. 6, or by the use of insert blocks 21^a, such as shown in Figs. 7 and 8, in which the pockets are formed and which are secured in any suitable way in recesses in the valve body. The metal of such inserts may be of the same or different character from that of the body of the rotary member. The top area of these inserts should be substantially the same as the area of the ports or pockets at the surface of the valve body, the metal of the inserts surrounding the pockets being preferably tapered to thin edges 22 at the top, which edges desirably terminate slightly below or inside the surface of the valve body. If desired, asbestos or heat-insulating material could be interposed between the linings 21 or the inserts 21^a and the faces of the recesses in the valve body.

What I claim as new is:

1. An internal combustion valve comprising a casing having a bore with intake and exhaust openings at opposite sides, which are connected alternately with the cylinder by transfer ports in a rotor turning in the bore, the rear edge of the intake opening into the bore being beveled so as to form with the surface of the rotor a wedge-like entrance for lubricant.

2. A rotary valve for internal combustion engines comprising a rotary valve body turning in the bore of a casing and having an external pocket for connecting intake and exhaust openings at opposite sides alternately with the cylinder, and an internal longitudinal passage through which the fresh gases are caused to pass, the said valve body being provided with lubricant-catching recesses in the surface of its interior passage and with means for conducting the oil from said recesses to its outside surface.

3. A rotary valve for internal combustion engines comprising a rotary valve body turning in the bore of a casing and having an external pocket for connecting intake and exhaust openings at opposite sides alternately with the cylinder, and an internal longitudinal passage through which the fresh gases are caused to pass, the said valve body being provided with lubricant-catching recesses in the surface of its interior passage, means for conducting the oil from

said recesses to the outside surface, and external oil grooves communicating with said means.

4. A rotary valve for internal combustion engines comprising a rotary driven valve body turning in the bore of a casing and provided with a port controlling the exhaust, the exterior of the valve body where it borders on said port being lowered to allow for unequal expansion.

5. A rotary valve for internal combustion engines comprising a rotary driven valve body turning in the bore of a casing and provided with a port controlling the exhaust, the surface of the valve body in the port zone and more especially immediately adjacent the port being lowered to allow for unequal expansion.

6. A rotary valve for multicylinder internal combustion engines comprising a casing formed with a bore and having ports to the cylinders and intake and exhaust ports

at opposite sides, and a rotary valve body having external pockets constituting transfer ports for connecting said intake and exhaust ports alternately with the cylinder ports, the said valve body being characterized by the portions of its surface bordering on the ports being sufficiently lower than the general surface to prevent an elevation at 30 the port lips when the body is exposed to the heat of the exhaust gases. 25

7. In a rotary valve for internal combustion engines, comprising a casing having a valve seat bore provided with an exhaust port and a port communicating with the cylinder, a valve body turning in said bore and having an external pocket constituting a transfer port for connecting the exhaust and cylinder ports, the surface of 40 the valve body bordering upon the rear lip of the transfer port being slightly cut down or beveled as and for the purpose set forth. 35

EUGENE M. BOURNONVILLE.
